UNITED STATES PATENT OFFICE.

PAUL B. WERNER, OF PHILADELPHIA, PENNSYLVANIA.

METHOD AND MEANS TO CONTROL INDUCTION-COILS.

1,258,838.

Specification of Letters Patent. Patented Mar. 12, 1918.

Application filed March 24, 1915. Serial No. 16,542.

To all whom it may concern:

Be it known that I, PAUL R. WERNER, a citizen of the United States, residing in the city and county of Philadelphia, State of Pennsylvania, have invented a new and useful Method and Means to Control Induction Coils, of which the following is a specification.

My present invention relates to novel means to control and energize an induction coil and relates more particularly to an electromagnetic controlled induction coil, in which the coil is saturated before opening the circuit, whereby my device is especially adapted to be employed for the ignition of internal combustion engines.

It further consists of a novel apparatus, wherein I employ a contact to establish a circuit through the induction coil, and immediately thereafter, I provide for the establishing of another circuit, both of said circuits being in parallel, and I then employ the second circuit to open the first circuit.

The main object of my present invention is to devise a construction, wherein a complete saturation of the induction coil is effected, prior to the opening of the circuit, the result of which is that I am enabled to obtain a greatly increased efficiency from any given induction coil.

Other novel features of construction and advantage will hereinafter more clearly appear in the detailed description.

For the purpose of illustrating my invention, I have shown herein a typical embodiment of my invention, which will give satisfactory and reliable results in practice, although it is to be understood that the various instrumentalities of which my invention consists can be variously arranged and organized and that my invention is not limited to the precise arrangement and organization of these instrumentalities as herein shown and described.

Figure 1 represents, diagrammatically, a means embodying my invention for controlling induction coils.

Fig. 2 represents in sectional elevation, a portion of a contact making mechanism.

Similar numerals of reference indicate corresponding parts in the figures.

Referring to the drawings:—

1 designates a source of electric supply which may be of any desired nature, but, in the present instance, I have preferred to

illustrate the same as consisting of a battery, which is connected with the ground by a line 2.

3 designates a line leading to a means 4, for opening or closing the circuit, such as for example, the contact mechanism illustrated. The contact mechanism 4 is provided with a contact carrying member 5, to which is connected a line 3. The member 5 is provided with a contact 6, which operates with a stationary contact 7, adjustably mounted, since it is carried by a screw 8. 9 designates a stop for the contact carrying member 5. 10 designates a line leading to a primary coil 11 of an induction coil 12 which is provided with a secondary coil 13. 14 designates a condenser, illustrated as connected on opposite sides of the primary coil 11. 15 designates a line leading from the primary winding 11 and communicating with a line 16, which is connected with a series of four contacts 17, it being understood that any desired number of contacts may be employed. I have preferred to illustrate four contacts as being made during a cycle of the contact mechanism 32.

The current flows from the contacts 17 through a brush 18 which is loosely mounted in an arm 19 carried by a rotatable shaft 20 which is connected with the ground by the line 21, so that the contacts 17 are grounded through the brush 18. The brush 18 is loosely mounted in the arm 19 and rests upon the weighted end 22 of an arm 23 pivoted at 24 to the arm 19.

25 designates a stop to limit the downward movement of the weighted arm 23. The source of electric supply 1 is connected by a line 26 with an electro-magnet 27 which is connected by a line 28 with a set of contacts 29 corresponding in number to the contacts 17. The contacts 29 are grounded through the brush 18, arm 19, shaft 20 and line 21 in a similar manner to that in which the contacts 17 are grounded. When the magnet 27 is energized through the contact of the brush 18 with the contact 29, the armature 30 carried by the contact carrying member 5 will be attracted, thereby separating the movable contact 6 from the relatively stationary contact 7, thereby opening or breaking the circuit through the primary coil.

During the cycle of the operation, the shaft 20 may be rotated in either direction

- in accordance with the manner in which it is to be used, and in the present instance, it is illustrated as rotating counter clockwise or in the direction of the arrow seen in Fig. 1, 5 and the contacts 29 are illustrated as located posterior to the contacts 17, it being understood that if the arm 19 is to be rotated in a reverse direction, the contacts 29 will then be placed on the opposite side of the contacts 17. The centrifugal force will cause the weighted arm 23 to move upwardly, thereby bringing the brush 18 into position to successively make contacts with the contacts 17 and 29. When the brush 18, rotating in the direction of the arrow, contacts with the stationary contacts 17, the circuit is closed through the primary coil 11 and the primary coil is completely saturated, it being understood that the operative length of the contacts 17 and 18 may be made of sufficient length to provide for a complete saturation of the primary coil under high speeds of the arm 19. Before the brush 18 breaks the circuit, it comes into contact with the contact 29, which establishes a circuit through the electro-magnet 27, thereby breaking or opening the primary circuit, since the armature 30 is attracted by the magnet 27, as is apparent. Since the current is interrupted, no arcing can take place between the contacts 18 and 17. As the contact between the contacts 18 and 29 is broken, due to the further rotation of the arm 19, only a very slight arcing is possible, since the electro-magnet 35 is constructed to take but a minimum amount of current. Since the arcing is practically eliminated, the durability of the contacts 17, 29 and 18 is greatly increased with consequent economy in the cost of operation. 40 Since I employ electro-magnetic means to open the circuit in the primary winding, a separation of the contact is effected in a minimum amount of time, which provides for a rapid deenergizing of the primary coil and a consequent highly efficient secondary current. The secondary winding 13 has one end grounded through the primary circuit and the other end 31 is grounded through the usual distributing means. 45 It will be apparent that the secondary circuit can be arranged in any desired manner, for example, instead of grounding one end through the primary, it may go to another spark plug or distributor. 50 It will also be apparent that any other device, besides an induction coil, requiring a given amount of current, can be used in this method and is within the scope of my claims. 55 On a further revolution of the arm 19, 60 the circuit is opened and closed in the different circuits in a similar manner to that already described. The number of times in which this opening and closing of the two circuits is performed in a cycle of the rotation of the shaft 20 will depend entirely

upon the number of sets of contacts employed, such as 17 and 29.

It will, of course, be understood that it is within the scope of my invention to employ any desired means for bringing the contact 18 into successive engagement with sets of contacts, such as 17 and 29, and a sliding contact illustrated is simply one manner of accomplishing this result.

In my present invention, I form a circuit 75 which carries the current to the induction coil in undiminished strength for a length of time which is determined only by the requirements met with in practice. As the speed of the engine increases, the shaft 20, 80 which is driven by the engine, causes the contacts to become shorter in time, and it is therefore desirable to make the contacts long enough under high engine speed to allow a complete saturation of the induction 85 coil. At lower speed, there will then be an excess of current flowing through the induction coil, which will, however, not counter-balance, the great advantage obtained in securing at all times a complete saturated coil 90 and a correspondingly efficient spark.

In order to interrupt the current flowing through the primary coil, I immediately, on closing the primary circuit, close the other circuit through the interrupting means to 95 break and hold open the primary circuit until the brush 18 leaves the contact 17 so that only one break is produced in the primary circuit of the induction coil, said break being made by the contact mechanism 4. As 100 the primary circuit has had sufficient time to thoroughly saturate the induction coil, the spark produced is the maximum spark which can be obtained from a given induction coil. It will be apparent that the contact carrying member 5 is maintained in its downward position and the primary circuit remains open until the brush 18 leaves the contact 29. When the contact 18 comes into engagement with the contact 17, the circuit 110 is established through the primary circuit, and the circuit is interrupted by the contact 18 coming into engagement with the contact 29, so that the electro-magnet 27 and the induction coil 12 are at such time in parallel, 115 and remain so for a brief interval of time until the armature 30 is attracted and the primary circuit opened. The contact 18 leaves the contact 17 without producing a spark, since the main current is still interrupted by the armature 30 being attracted by the magnet 27, due to the current flowing through the electro-magnet circuit, as the brush 18 is in contact with a brush 29. During the interval of time in which the brush 125 18 is passing from a brush 29 to the next contact 17, no current is flowing through either circuit. It will also be apparent that in case the engine stops, the arm 23 will move downwardly and the brush 18 will not 130

be in a position to engage the contact 17 or 29. It will thus be seen that the contact mechanism can not stop on short circuit.

I am aware that it has heretofore been proposed to employ an electro-magnetic making and breaking device in which both of the coils are simultaneously energized. This does not give the best results in practice, since the induction coil will not receive the entire magnetization of its core on account of the coil of the magnet being energized at the same time and interrupting the main or primary circuit before it has had an opportunity of building up the full saturation of the magnetic field. This causes a very erratic working of the induction coil and consequent inefficiency, due to the fact that the coil cannot be fully saturated. My invention is clearly differentiated from such construction, as is apparent.

In so far as I am aware, I am the first, in the art to provide, in a device of this character, means for the complete saturation of the induction coil and the consequent advantages arising therefrom, and my claims are to be interpreted with corresponding scope.

It will now be apparent that I have devised a novel and useful means to control an induction coil, which embodies the features of advantage enumerated as desirable in the statement of the invention and the above description, and while I have, in the present instance, shown and described a typical embodiment thereof which will give in practice satisfactory and reliable results, it is to be understood that the same is susceptible of modification in various particulars without departing from the spirit or scope of the invention or sacrificing any of its advantages.

It will also be apparent that in accordance with my present invention, I have devised a novel method of igniting internal combustion engines, wherein I form a primary circuit including an induction coil, the secondary coil being utilized to ignite the explosive charges in the different engine cylinders. I then form another circuit which includes means, such as for example, an electro-magnet, to open the primary circuit. The closing of both circuits is effected by mechanical means controlled by the engine. The closing of one circuit effects the opening of the other circuit. The circuit which opens the primary circuit is opened by means controlled by the engine.

It will thus be seen that I form an electric circuit, part of which is formed of separate circuits. The separate circuits are then closed. A secondary circuit is formed and the closing of one of the separate circuits causes the opening of the other separate circuit and thereby a current is formed in the secondary or high tension circuit,

which ignites the explosive charge in the proper engine cylinder. Thereafter, the second separate circuit is opened.

Having thus described my invention, what I claim as new and desire to secure by Letters Patent, is:—

1. An electric circuit, electro-magnetic means to open said circuit, means to close said circuit, and means to prevent short-circuiting of said circuit. 75

2. An electric circuit, electro-magnetic means to open said circuit, means to automatically close said circuit, and means to prevent short-circuiting of said circuit.

3. Electric circuits, means for closing said circuits, the closing of one circuit effecting the opening of the other circuit, and the means for closing one of said circuits including devices incapable of stopping on short-circuit. 80

4. Electric circuits, and mechanical means for closing said circuits, the closing of one circuit effecting the opening of the other circuit, said mechanical means being incapable of stopping on short-circuit. 85

5. An electric circuit, a second electric circuit, and mechanical means to close said circuits, the closing of the second circuit effecting the opening of the first circuit, and said circuits including a battery common to each 95 circuit.

6. An electric circuit, a second electric circuit, and mechanical means to close said circuits, the closing of the second circuit effecting the opening of the first circuit, and said mechanical means effecting the opening of said second circuit, and said circuits including a battery common to each circuit. 100

7. An electric circuit, a second electric circuit, and mechanical means to close said circuits, the closing of the second circuit effecting the opening of the first circuit, and said mechanical means effecting the opening of said second circuit, and said means being incapable of stopping on short circuit. 105

8. The method of igniting internal combustion engines, which consists in forming electric circuits, closing two of said circuits, and effecting the opening of one of the two circuits by the closing of the other of said two circuits to produce a spark in a third circuit, and then effecting the opening of the other of the two circuits, said circuits having a common source of energy. 115

9. The method of igniting internal combustion engines, which consists in forming an electric circuit, part of which is formed of separate circuits, closing one of the separate circuits, forming a secondary circuit, closing the other of the separate circuits to effect the opening of the first separate circuit and thereby a current in the secondary circuit, and then opening the second separate circuit. 120

10. In an ignition system, a transformer 130

coil, and means including a single source of energy to effect the electrical operation thereof, said means including devices to fully saturate a portion of the transformer coil.

11. In an ignition system, a circuit including a coil, and including a single source of energy, means to open the circuit, and means to fully saturate the coil prior to the 10 opening of the circuit.

12. In an ignition system, means to utilize the current from a single source of energy to saturate an induction coil, said means including an electric circuit to cause the current from the same source to deenergize the 15 induction coil to produce an efficient spark.

13. In an ignition system, means to utilize the current from a single source of energy to saturate an induction coil, said means causing the current from the same source to deenergize the induction coil to produce an 20 efficient spark, each of said means being incapable of short-circuiting.

14. In an ignition system, means to utilize the current from a battery to saturate 25 an induction coil, said means including an

electric circuit to cause the current from the same battery to deenergize the induction coil to produce an efficient spark.

15. In an ignition system, electric circuits 30 having a single source of energy and having contacts alternately arranged in spaced relationship, and mechanical means having a single contact to successively engage contacts of different circuits, and one of said 35 circuits having electro-magnetic means to open another circuit.

16. In an ignition system, electric circuits having a single source of energy and having contacts alternately arranged in spaced 40 relationship, and mechanical means having a single contact to successively engage contacts of different circuits, to successively effect the closing of one circuit, the closing of the second circuit, the opening of the first 45 circuit, and the opening of the second circuit.
